UNITED STATES PATENT OFFICE.

ALFRED A. GLIDDEN AND FRANK D. BEAN, OF WATERTOWN, MASSACHUSETTS, AS-SIGNORS TO HOOD RUBBER COMPANY, OF WATERTOWN, MASSACHUSETTS, A CORPORATION OF MASSACHUSETTS.

FOOTWEAR.

Application filed September 2, 1924. Serial No. 735,373.

To all whom it may concern:

Be it known that we, ALFRED A. GLIDDEN and FRANK D. BEAN, citizens of the United States, and residents of Watertown, in the 5 county of Middlesex and State of Massachusetts, have invented certain new and useful Improvements in Footwear, of which the following is a specification.

Our present invention relates to improvements in footwear of the type known as 10 "arctics" embodying a rubber lower or foot portion and a flexible cloth upper or ankle and leg enclosing portion.

The invention aims to provide a construction which may be quickly put on and removed, and which will be kept properly closed and of slight appearance when on 15 the foot, having no exposed fasteners, and those used being reduced to a minimum 20 number.

The invention further aims to provide a shoe of this type which may be produced at an extremely low cost.

With these several objects in view, the invention 25 includes the novel features of construction and arrangement and combination of parts hereinafter described, the invention being defined by the claims appended hereto.

An embodiment of our invention is illustrated in the accompanying drawings, in 30 which:

Figure 1 is a perspective view of the improved article in closed condition, as it would appear when worn.

Fig. 2 is a front view of the shoe open 35 and ready to be drawn on the foot.

Fig. 3 is a partial section on line 3—3 of Fig. 1, and

Fig. 4 is a partial section on line 4—4 of 40 Fig. 1.

Referring by reference characters to this drawing, the numeral 1 designates the rubber portion of the shoe and 2 the cloth upper, which may be of the ordinary or any 45 desired construction. It is obvious that the height to which the rubber portion extends is immaterial, being shown herein as extended only a short distance above the sole, as is desirable in a lady's arctic, which is 50 that selected for the present embodiment of the invention. The upper has the usual open or divided front provided with a "bellows" or "accordion" insert 3, the edges of

which are secured to the upper, adjacent the divided edges thereof, whereby a complete 55 water-proof closure is formed over the instep and front of the leg, this bellows insertion permitting the upper, when its edges are unfastened or disconnected, to expand sufficiently to allow it to be easily drawn on 60 and off.

For securing the edges of the upper together we provide a plurality of fasteners which are concealed from view when the upper is closed, and these fasteners preferably take the form of hook and eye members 4 and 4^a, two sets or pairs only being 65 preferably used, and being preferably of wire loop form, as shown, and capable of being readily engaged and disengaged.

The fasteners are attached back from the edges so that the edges may be turned back to allow the fasteners to be readily manipulated, whereafter the resiliency of the edge material will cause them to assume closed 75 position with their edges in abutting contact. The fasteners are conveniently secured to the upper by loops of double tape, or the like, 5^a, adhesively secured between the upper 2 and its lining 2^a, to the edges 80 of which lining the edges of the bellows insert are secured.

To prevent the portions of the edges between each pair of fasteners, and between the lower pair and the bottom of the division slit of the upper from opening up, for in other words, to maintain the edges in contact throughout their entire extent, we provide reinforcing stays 5 of thin resilient material, such as thin strips of steel, which are embedded in the edges, and in a shoe using two pairs of fasteners four of these are provided, two in the edges between the lower pair of fasteners and the bottom of the division slit, and two between the two 95 pairs of fasteners.

These stays are of sufficient flexibility to readily conform to the shape of the limb of the wearer, but effectually prevent any tendency of the edges to separate, as any strain 100 in this direction is edgewise of the stays and hence strongly resisted. By reason of the interruption of the stays at the lower pair of fasteners, the edges of the upper can flex readily at this point, which facilitates the 105 engaging of the fasteners. The upper ends

of the upper pair of stays, for a similar reason, terminate just below the upper pair of fasteners.

Preferably we incorporate in each edge of the upper division a relatively thick and wide strip of rubber 6, which, while amply flexible, yet stiffens the edges and by reason of its resiliency causes the edges to remain in abutting contact.

10 A shoe as thus constructed can be readily put on and removed, can be quickly fastened and unfastened, and when in position on the foot of the wearer will be kept closed with no unsightly fastening means in view or exposed to catch on the dress.

Having thus described our invention, what we claim is:

1. An article of footwear of the class described having a plurality of pairs of separable metallic fasteners secured to the inner face of the upper somewhat back from the edges, and a narrow strip of resilient rubber incorporated in each of said edges.

2. A front opening article of footwear of the arctic type, having a plurality of pairs of interengaging fasteners secured to the inner face of the upper sufficiently back from the edges to cause the inter-engaging portions of the fasteners to lie approximately flush with the edges, whereby when the cooperating fasteners are engaged the edges will be held in abutting position and the fasteners concealed.

3. An article of footwear of the class described having a plurality of pairs of cooperating fasteners secured to the inner face of the upper somewhat back from the edges, strips of resilient rubber incorporated in said edges, and stays also incorporated in said edges, the rubber strips being wider than said stays.

4. An article of footwear of the front opening arctic type, having a pair of interengaging fasteners secured to the edges ad-

45 jacent the top and a similar pair intermediate the top and bottom of the opening, said fasteners being secured to the inner face of the upper sufficiently back from the edges to cause the interengaging portions of the fasteners to lie approximately flush with the edges whereby, when the cooperating fasteners are engaged, the edges will lie in abutting position, and the fasteners be concealed, and resilient stays incorporated in 50 said edges between said fasteners and between the lowermost fasteners and the bottom of the opening.

5. An article of footwear of the "arctic" type having a rubber lower portion and a flexible cloth upper provided with a front opening, said upper having a pair of cooperating metallic fasteners of the hook and eye type secured to the upper approximately at the ankle line, and another pair adjacent the top, said fasteners being secured to the inner face of the upper relatively remote from the edges and with the edges of the upper in substantial alignment with the free ends of the fasteners.

6. An article of footwear of the "arctic" 70 type having a rubber foot portion and front opening upper, said upper having two pairs of resilient stays incorporated in its edges, one pair of stays extending from the bottom of said front opening to approximately 75 the ankle line, and the other from said ankle line upward therefrom, cooperating hook and eye members articulated to the inner face of the upper back of the line of said stays adjacent the space between the upper and lower pairs, and having their free ends in substantial alignment with the edges of the upper, and fastening means at the top of the upper.

In testimony whereof we affix our signatures.

ALFRED A. GLIDDEN.
FRANK D. BEAN.
